UNITED STATES PATENT OFFICE.

FANNY KLASS, OF SAN FRANCISCO, CALIFORNIA.

COMBINATION FRONT AND BACK REDUCER.

1,218,414.

Specification of Letters Patent.

Patented Mar. 6, 1917.

Application filed October 31, 1916. Serial No. 128,700.

To all whom it may concern:

Be it known that I, FANNY KLASS, a citizen of the United States, residing in the city and county of San Francisco and State of California, have invented new and useful Improvements in Combination Front and Back Reducers, of which the following is a specification.

This invention relates to a combination front and back reducer.

The object of the present invention is to provide a simple, cheaply manufactured, easily applied front and back reducer constructed of a sectional elastic front adapted 15 to support or hold up a woman's breasts, and a back section coöperating therewith consisting of a pair of interspaced elastic bands connected by a plurality of vertically positioned steels.

20 Further objects will hereinafter appear.

The invention consists of the parts and the construction and combination of parts as hereinafter more fully described and claimed, having reference to the accompanying drawings in which—

Figure 1 is a perspective view showing the application of the invention.

Fig. 2 is a perspective view of the front and back reducer.

30 Fig. 3 is a front view of the invention.

Fig. 4 is an inside view of the back section.

It is a well known fact that women as a whole are rather particular as regards their 35 figure, and especially the bust. Although a woman may have a full and rounded chest, and comparatively speaking well developed and rounded breasts, it often happens that these are placed too low, or extend too far

40 under the arms to give the possessor a good form without artificial support of some kind. Corsets are largely worn with this object in view, but do not always accomplish the object sought. Any artificial support worn 45 should be so constructed as to brace and hold up the breasts, and should in most cases also press them away from the arms laterally toward each other to permit the bust to have a full and rounded appearance.

50 With this object in view, a front and back supporter and reducer of the character shown has been provided. This consists of two cup-shaped sections 2 and 3 constructed of an elastic material, which are adapted 55 to inclose and support the breasts. These sections may be secured together in any

suitable manner or as here shown by the hooks and eyes. The back section consists of two comparatively wide bands 5 and 6 which are spaced apart as at 7 to permit a 60 free ventilation and to prevent the wearer from becoming overheated. These sections are held apart and secured together in this instance by three vertically positioned steels such as indicated at 8, 9, and 10. The individual front sections 2 and 3 are secured to the vertical steels 8 and 10 by sewing or as here shown by hooks and eyes 4.

A reducer and supporter constructed as here shown eliminates the necessity of wearing a corset of any kind. First of all it has the capacity of lifting and supporting the breasts where their position is comparatively low, second if the breasts have a tendency to extend under the arms, it can readily 75 be seen that they are pulled forward and together by means of the upper elastic band 5 passing under the arms, and the elastic front sections 2 and 3. The lower band 6 coöperates with the upper band to maintain 80 a fixed position and at the same time supports the back and thereby relieves such pains as are generally developed when a corset is not worn. The device not only supports the breasts and gives the bust as a 85 whole a full and rounded appearance, but it also reduces the bust in its entirety, as it squeezes in and supports the fatty or heavy portions under the arms and breasts. The simplicity of construction permits it to be 90 cheaply manufactured and quickly applied, and as the back section is comparatively open, it can readily be seen that it may be worn with perfect comfort without overheating the wearer or hindering any freedom of movement so far as the arms are concerned or otherwise.

Women being athletically inclined can therefore wear the garment described, where a corset would be entirely out of the question.

100 While the front and back sections are worn as a combined garment, it is obvious that the front sections may be attached to any other garment if desired. I similarly 105 wish it understood that the materials and finish of the several parts of the garment may be such as the experience and judgment of the manufacturer may dictate. The lower strap also supports the back to such an 110 extent that a weak back will be strengthened and a strong back supported, so that com-

paratively heavy loads can be lifted without danger of straining.

Having thus described my invention, what I claim and desire to secure by Letters Patent is:

A brassière including a pair of cup-shaped breast supporting sections, means to connect the inner ends of said sections, a back composed of upper and lower spaced and comparatively wide bands, and transverse steels connecting said bands and extending across the space therebetween, said steels being

disposed at the centers and ends of the bands, and means between the end steels and the outer ends of the sections to removably connect said parts.

In testimony whereof I have hereunto set my hand in the presence of two subscribing witnesses.

FANNY KLASS.
